DRILL STEEL CENTRALIZER

John C. Curtis, Claremont, N. H., assignor to Sullivan Machinery Company, a corporation of Massachusetts

Application July 21, 1941, Serial No. 403,374

26 Claims. (Cl. 255—51)

This invention relates to rock drills, and more particularly to a centralizer for a drill steel actuated by a rock drill of the hammer type.

In drilling material such as rock it is sometimes very difficult to maintain the drill bit in axial alinement with the rock drill. This is particularly true when starting horizontal holes in uneven rock surfaces. Under such conditions the working end of a rapidly rotating drill steel whips about, making it difficult to start the hole correctly. The whipping action may be due partly to the flexibility of the drill steel and partly to the clearances between the drill steel and the chuck mechanism of the rock drill into which the drill steel extends. As the chuck mechanism becomes worn the play between the parts increases and, in time, the action of an unsupported drill will interfere with the operation of the chuck rotation mechanism. If the drill steel is permitted to drift out of alinement with the longitudinal axis of the drill, there will be produced a binding between the drill steel and its work, thereby increasing the load on the drill motor and causing excessive wear on the gaging surfaces of the cutting bit.

It is an object of this invention to provide improved means for guiding the drill steel during a portion of the drilling operation. Another object of the invention is to provide an improved drill steel centralizer having improved means for positively locking guide members in position for guiding the drill steel during the starting of the drill hole. Still another object is to provide improved means for holding a drill steel in axial alinement with its actuating motor during a portion of the drilling operation and automatically operative, when the hammer motor reaches a predetermined point in its feed, to release the drill steel and move out of the path of the motor. Another object is to provide an improved drill steel guide of the pivoted guide arm type wherein the guide arms may be individually swung about their pivots into guiding relation with the drill steel, and having individual locking means. Other objects of the invention will, however, hereinafter more fully appear in the course of the following description.

In the accompanying drawing there is shown for purposes of illustration one form which the invention may assume in practice.

In the drawing—

Fig. 1 is a side elevational view of a portion of a drill mechanism having embodied therein one illustrative form of the improved centralizer.

Fig. 2 is a view taken on the plane of the line

2—2 of Fig. 1, and showing the guide members of the centralizer engaging the drill steel.

Fig. 3 is a view similar to Fig. 2, but showing the guide members in their released positions.

Fig. 4 is a plan view with parts broken away showing the centralizer and the forward portion of the guide shell.

Fig. 5 is an enlarged sectional view taken on the planes of the line 5—5 of Fig. 2.

Fig. 6 is a sectional view taken on the plane of the line 6—6 of Fig. 5.

Fig. 7 is a cross sectional view taken on the line 7—7 of Fig. 5.

In the drawing, to illustrate the invention, I have shown the front ends of a hammer drill and of a guide shell, designated, respectively, 1 and 2. A drill steel 4 is shown with its shank extending into the front head of the rock drill to receive the blows of a hammer piston (not shown), and secured to the outer end of the drill steel is a cutting bit 6 which is shown here as being of the detachable type.

The rock drill has the usual guide flanges 8 which are slidably received in guideways 9 in the shell 2 to enable the rock drill to be moved and guided relative to the work during drilling and retraction. Formed on the guide shell is a trunnion portion 10 adapted to be clamped in a suitable saddle of any well known form of rock drill support.

Attached to the forward end of the guide shell is a drill steel centralizer, generally designated 12, constructed in accordance with the practice of the invention. The drill steel centralizer comprises a support member 14 herein shown as having a plate portion 15 extending across the front end of the guide shell and providing a bearing for the front end of a feed screw 16. Obviously the feed screw 16 may be otherwise supported.

Projecting forwardly from the plate portion at its outer ends are cylinder portions 17 having bores 18 opening through their forward ends. Abutting the forward ends of the cylinder portions 17 are cylinder portions 20 of a transverse member 21,

and formed in the cylinder portions 20 are bores 22 in axial alinement with the bores 18 and opening into the latter. The members 14 and 21 are firmly secured to the front end of the guide shell by bolts 24 extending axially through the cylinder portions 17 and 20.

The centralizer includes guide members 25 for guiding the drill steel during a portion of the drilling operation, and these guide members include arms 26 having hub portions 27 which are received in the bores 18 and 22 and are provided

with openings 28 extending therethrough for receiving the bolts 24. The arms 26 project from the hub portions 27 outwardly through openings 30 in the walls of the cylinder portions 17 and are provided at their outer ends with curved recesses 31 for receiving the drill steel when the arms are moved to their drill-steel-guiding positions. The openings 30 are of such angular extent that the guide members may swing from their drill-steel-guiding positions outwardly far enough to permit the rock drill to pass between them, and the dimensions of the openings longitudinally of the cylinder portions are somewhat greater than the corresponding dimensions of the arms 26 so that the guide members may be moved bodily or translationally relative to the cylinder portions for a reason to be shortly explained. The surfaces at the outer edges of the openings 30 act as abutments for limiting the outward swinging movement of the guide members.

Means are provided for yieldably urging the guide members 25 toward their outer angular positions and toward the rear ends of the cylinder bores 18. This means comprises coiled springs 33 surrounding the portions of the bolts 24 extending through the bores 22 and having their forward ends fixed to the cylinder portions 20 and their rear ends fixed to the hubs 27 of the guide members. Formed in the cylinder portions 17 at the rear ends of the bores 18 are recesses or grooves 35 for receiving projecting portions, such as tongues 36, on the rear ends of the hubs 27 when the guide members are in their drill-steel-guiding positions. Due to the force exerted by the springs 33, the hubs 27 of the guide members are held firmly against the end walls of the bores 18, so that frictional contact between the hubs and the end walls of the bores aids in holding the guide members in their released positions, and when the guide members are moved to positions for engaging the drill steel the tongues 36 move into the grooves 35 and effect a locking of the guide members in such positions. When the guide members are moved forwardly relative to the cylinder portions 17 a sufficient distance to remove the tongues 36 from the grooves 35, the springs 33 cause the members to swing outwardly about the bolts 24 until the arms 26 engage the outer edges of the openings 30. Formed on the rear faces of the arms 26 are projecting abutments 38 which are engaged by the front end of the rock drill for forcing the guide members forwardly relative to the cylinder portions 17 and effecting a release of the tongues 35 from the grooves 36.

In the operation of the device, whenever it is desired to start a new drill hole the guide members 25 may be swung into positions for engaging the sides of the drill steel, and the members are forced rearwardly by the springs 33 to effect a seating of the tongues 36 in the grooves 35 for locking the guide members against any angular movement. The members remain in their guiding positions during the drilling of the hole until the front end of the rock drill advances into contact with the abutments 38 on the arms 26 and forces the guide members bodily ahead to release the tongues from the grooves 35. Upon release of the tongues from the grooves, the guide members are swung outwardly by the springs 33 so that the drill may continue its advancing movement until the working implement has penetrated the material to the limit of its extent. The guide arms may be placed individually in guiding positions so that but a single guide arm may be used

if that is all that is necessary in spotting a hole.

As a result of this invention it will be noted that the drill bit upon the drill steel will be held coaxial with the rock drill during the early portion of the drilling operation so as to prevent any departure of the drill from its desired course. It will be further noted that the guide members are positively locked in their guiding positions until the drill has advanced a predetermined distance, at which time the guide members are released and automatically moved out of the path of the drill. It will be evident that by suitably interconnecting the guide members, as by gear sectors or the like, locking and turning means applied to either member may control both members without departing from the spirit or the scope of my invention.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a drill steel centralizer, in combination, a support, a pair of guide members pivotally mounted on said support on axes parallel to the longitudinal axis of a drill steel to be guided and swingable relative to each other into guiding and non-guiding position, means carried by said guide members and engageable with said support for positively locking said guide members against outward swinging movement from their steel guiding position, and yielding means operatively connected to said guide members for always positively moving said guide members to their non-guiding position whenever said locking means is released, said locking means when in locking position locking said guide members inwardly in steel guiding position against the action of said yielding means.
2. In a drill steel centralizer, in combination, a support, a pair of guide members pivotally mounted on said support on spaced parallel axes extending longitudinally of a drill steel to be guided and swingable into guiding and non-guiding positions, means for positively locking said guide members individually in their guiding position, and yielding means operatively connected to said guide members for always individually positively moving said guide members to their non-guiding position whenever said locking means is released.
3. In a drill steel centralizer, in combination, a support, a pair of guide members pivotally mounted on spaced parallel axes on said support for movement into guiding and non-guiding positions, said guide members being movable bodily relative to said support when in their guiding positions for effecting a locking of said guide members against pivotal movement, and yielding means for positively moving said guide members to their non-guiding positions when the latter are moved to positions for pivotal movement, said yielding means acting on said guide members positively to move the same in a locking direction as well as in a direction towards non-guiding positions.
4. In a drill steel centralizer, in combination, a pair of guide members pivotally mounted on axes extending parallel to a plane including the longitudinal axis of the drill steel for movement

into guiding and non-guiding positions, said guide members being movable jointly longitudinally of their pivotal axes when in their guiding positions for effecting a locking of said guide members against pivotal movement, and yielding means for continuously urging said guide members about their pivotal axes toward their non-guiding positions.

5. In a drill steel centralizer, in combination, a pair of guide members pivotally mounted on axes extending parallel to a plane including the longitudinal axis of the drill steel for movement into guiding and non-guiding positions, said guide members being movable longitudinally of their pivotal axes when in their guiding positions for effecting a locking of said guide members against pivotal movement, and yielding means for continuously urging said guide members longitudinally of their pivotal axes toward positions in which said members are locked against pivotal movement, said guide members being releasable automatically by concurrent longitudinal movement along their pivotal axes.

6. In a drill steel centralizer, in combination, a pair of guide members pivotally mounted on axes extending parallel to a plane including the longitudinal axis of the drill steel for movement into guiding and non-guiding positions, said guide members being jointly movable longitudinally of their pivotal axes when in their guiding positions for effecting a locking of said guide members against pivotal movement, and yielding means for continuously urging said guide members longitudinally of their pivotal axes toward positions in which said members are locked against pivotal movement and angularly about their pivotal axes toward their non-guiding positions.

7. In a drill steel centralizer, in combination, a support having a pair of bores extending parallel to and on opposite sides of a plane including the longitudinal axis of the drill steel, a pair of guide members having hub portions received within said bores and arm portions projecting outwardly perpendicular to the axes of said bores, said guide members rotatable about the axes of said bores into guiding and non-guiding positions, means for positively locking said guide members against rotation when in their guiding positions, and means for continuously urging said guide members toward their non-guiding positions.

8. In a drill steel centralizer, in combination, a support having a pair of bores extending parallel to and on opposite sides of a plane including the longitudinal axis of the drill steel, a pair of guide members having hub portions received within said bores and arm portions projecting outwardly perpendicular to the axes of said bores, said guide members rotatable about the axes of said bores into guiding and non-guiding positions, means for positively locking said guide members against rotation when in their guiding positions including recesses in said support, projecting portions on said guide members receivable in said recesses, and means for continuously urging said guide members longitudinally of said bores toward said recesses.

9. In a drill steel centralizer, in combination, a support having a pair of bores extending parallel to and on opposite sides of a plane including the longitudinal axis of the drill steel, a pair of guide members having hub portions received within said bores and arm portions projecting outwardly perpendicular to the axes of said bores,

said guide members rotatable about the axes of said bores into guiding and non-guiding positions, means for positively locking said guide members against rotation when in their guiding positions including recesses in said support opening into one end of said bores, projecting portions on the hub portions of said guide members receivable in said recesses when the guide members are in guiding positions, and yielding means for continuously urging said guide members longitudinally of said bores toward said recesses and angularly about the axes of said bores toward non-guiding positions.

10. In a drill steel centralizer, in combination, 15 a support having a pair of bores extending parallel to and on opposite sides of a plane including the longitudinal axis of the drill steel, a pair of guide members having hub portions received within said bores and arm portions projecting outwardly perpendicular to the axes of said bores, said guide members rotatable about the axes of said bores into guiding and non-guiding positions, means for positively locking said guide members against rotation when in their guiding positions including recesses in said support opening into one end of said bores, projecting portions on the hub portions of said guide members receivable in said recesses when the guide members are in guiding positions, and coiled springs 20 connected to said support and to the hub portions of said guide members for continuously urging the latter longitudinally of said bores toward said recesses and angularly about the axes of said bores toward non-guiding positions.

11. In a drill steel centralizer, in combination, 25 a support having bores therein, guide members having hub portions received within said bores and projecting arm portions carrying steel engaging and guiding devices, said guide members 30 pivotable on axes coincident with the axes of said bores between guiding and released positions, and means for controlling the positions of said guide members including means for releasably locking them in guiding position while in 35 such position and for automatically moving them out of the way upon a predetermined movement while in such position.

12. In a device of the character described, a 40 drill steel guide member, means for mounting said guide member for pivotal movement on an axis parallel to the longitudinal axis of a steel to be guided and for translatory movement longitudinally relative to the steel, means constantly tending to swing said guide member about its 45 pivot out of steel guiding position, and means operative in a given position of said member and engaging said mounting means to hold said guide member in guiding position, said holding means rendered ineffective upon predetermined translatory movement of said guide member from said 50 given position out of held engagement with said mounting means.

13. In a drill steel guide, a guide element engageable with a drill steel, mounting means for 55 said guide element providing for pivotal and bodily movements thereof, locking means for holding said element in guiding position, said locking means being releasable upon bodily movement of said element, and resilient means for 60 yieldingly holding said guide element in locked position in guiding relation with the drill steel, said resilient means also automatically positively swinging said guide element about its pivot away from the drill steel into its released non-guiding 65 position whenever said locking means is released,

14. In a drill steel guide, a support, a pair of guide arms mounted on said support for pivotal and bodily movements, means for locking said guide arms in guiding position, said locking means being releasable upon bodily movement of said arms relative to said support, and torsion spring means arranged on said support and engaging said guide arms for automatically swinging the latter apart when said locking means is released.

15. In a drill steel guide, a support having locking means, a pair of guide arms mounted on said support for pivotal and bodily movements, locking projections on said arms engageable with locking means on said support for holding said arms against outward swinging movement from steel guiding position, and spring means tending to move said arms bodily relative to said support to bring said locking projections into locking engagement with said locking means, said locking projections being releasable from said locking means on said support upon bodily movement of said arms relative to said support against the action of said spring means and said arms when unlocked from said support being free to swing outwardly from steel guiding position.

16. In a drill steel guide, a support, a pair of guide arms, means for mounting said arms on said support for pivotal and bodily movements, and locking means on said arms and said support for locking said arms individually in guiding position, said locking means being releasable upon bodily movement of said guide arms in one direction relative to said support.

17. In a drill steel guide, a support, a pair of guide arms, means for mounting said arms on said support for pivotal and bodily movements, locking means on said arms and said support for locking said arms individually in guiding position, said locking means being releasable upon bodily movement of said guide arms in one direction relative to said support, and means for automatically swinging said guide arms to wide open position when said locking means is released.

18. In a drill steel guide, a support, a steel guiding element mounted on said support for movements with respect thereto in different directions in angularly related planes, locking means on said support and guiding element for locking the latter against movement in one plane relative to said support in steel guiding position, said locking means being releasable upon movement of said guiding element in a different plane relative to said support, and means operatively connected to said guiding element and always automatically operative whenever said locking means is released for positively moving said guiding element in said one plane out of guiding relation with the steel.

19. In a drill steel guide, a support, a pair of guide arms pivotally mounted on said support to swing individually relative thereto into and out of guiding positions, means on said arms and engageable with said support for locking said arms individually against outward swinging movement from steel guiding position, and constantly acting means operatively connected to said arms for always automatically positively swinging said arms either individually or concurrently outwardly into their non-guiding position whenever said locking means is released and for holding said arms in said non-guiding position, said locking means when in arm locking position holding said arms inwardly in guiding

relation with the drill steel against the action of said constantly acting means.

20. A centralizer for drill steels comprising a support, a pair of cooperating guide arms pivoted on parallel axes on said support for swinging movement in transverse planes with respect thereto, means carried by said arms and engaging said support for holding said guide arms against outward swinging movement from steel guiding position, and means operatively connected to said arms for automatically positively swinging said guide arms outwardly into non-guiding position whenever said holding means is released, said arm holding means holding said arms inwardly in steel guiding position against the action of said automatic swinging means.

21. In a drill steel guide, a support, a pair of cooperating steel guiding elements mounted on said support for movement into and out of steel guiding position, means on said support for confining said guiding elements during such movement in transverse planes perpendicular to the longitudinal axis of the drill steel, and separate locking devices, one individual to each guiding element, for separately or concurrently positively locking said elements in steel guiding position.

22. In a drill steel guide, a support, a pair of cooperating steel guiding elements mounted on said support for movement into and out of steel guiding position, means on said support for confining said guiding elements during such movement in transverse planes perpendicular to the longitudinal axis of the drill steel, separate locking devices, one individual to each guiding element, for separately or concurrently positively locking said elements in steel guiding position, and constantly acting means operable when said locking devices are released to effect movement of said guiding elements into their released non-guiding position.

23. A drill steel guide comprising a support, a guiding element mounted on said support for lateral movement into and out of guiding relation with a drill steel and for translatory movement in a direction longitudinally relative to the drill steel, and locking means on said guiding element and engageable with said support for locking said guiding element against outward lateral movement from steel guiding position, said locking means being releasable from locking engagement with said support upon translatory movement of said guiding element in one direction and said guiding element when unlocked from said support being free to move laterally outwardly from guiding relation with the drill steel.

24. A drill steel guide comprising a support, a guiding element mounted on said support for lateral movement into and out of guiding relation with a drill steel and for translatory movement in a direction longitudinally relative to the drill steel, locking means on said guiding element and engageable with said support for locking said guiding element in steel guiding position, said locking means being releasable from said support upon translatory movement of said guiding element in one direction, and yieldable means for urging said guiding element translationally toward its locked guiding position and effective when said locking means is released to move automatically said guiding element laterally out of guiding relation with the drill steel, said guiding element being movable translationally toward its unlocked position against the action of said yieldable means.

25. A drill steel guide comprising a support, a guiding element pivotally mounted on said support for swinging movement into and out of guiding relation with a drill steel and for translatory movement in a direction longitudinally relative to the drill steel, locking means on said guiding element and engageable with said support for locking said guiding element in guiding position, said locking means being releasable from said support upon translatory movement of said guiding element in one direction, a coiled torsion and compression spring for urging said guiding element translationally toward its locked guiding position and effective when said locking means is released from said support to swing automatically said guiding element out of guiding relation with the drill steel, said guiding element being movable translationally toward unlocked position against the action of said spring.

26. In a rock drill, the combination comprising a guiding support, a drill steel actuator guided on said support for movement toward and from

the work, and drill steel guiding means carried by said guiding support and including a guiding element mounted for longitudinal movement in a direction lengthwise of the drill steel and for lateral movement into and out of guiding relation with the drill steel, interlocking means on said support and guiding element for holding said guiding element in steel guiding position and releasable upon longitudinal movement of said guiding element relative to said support, said actuator as it moves forwardly along said guiding support toward the work being operative to effect movement of said guiding element longitudinally relative to said support to effect release of said holding means, and means effective when said holding means is released for moving automatically said guiding element laterally out of guiding relation with the drill steel and into a non-guiding position out of the path of movement of said actuator.

JOHN C. CURTIS.
